UNITED STATES PATENT OFFICE.

THOMAS MILLWARD, OF SAN FRANCISCO, CALIFORNIA.

CARBONATING-MACHINE.

1,259,894.

Specification of Letters Patent. Patented Mar. 19, 1918.

Application filed September 13, 1916. Serial No. 119,893.

To all whom it may concern:

Be it known that I, THOMAS MILLWARD, a citizen of the United States, residing at San Francisco, in the county of San Francisco, State of California, have invented a new and useful Carbonating-Machine, of which the following is a specification in such full and clear terms as will enable those skilled in the art to construct and use the same.

This invention relates to a machine for carbonating beverages and its object is to produce a machine which will use as little power as possible above that stored in the tanks from which the supply of water and CO₂ under pressure is obtained and is an improvement upon the invention disclosed in Patent No. 1,177,531, granted to me March 28, 1916, in that the present invention dispenses with the sniff valve disclosed in that patent and provides improved operating mechanism.

Another object of the invention is to produce a machine which will be capable of carbonating and discharging a small quantity of water with each operation thereof, the machine being small enough to be adaptable to bars and candy stores where the water is drawn off as it is carbonated.

Another object of the invention is to reduce the number of valves used in the construction of the machine to a minimum thereby reducing the weight and cost of the completed machine.

An embodiment of the invention is shown in the drawing in which the same reference numeral is applied to the same portion throughout, but I am aware that there may be many modifications thereof.

Figure 1 is an end view of the complete machine showing the water supply tank, the gas mixing tank and discharge spout,

Fig. 2 is a side elevation of the machine looking from the left of Fig. 1,

Fig. 3 is a side elevation of the machine looking from the right of Fig. 1,

Fig. 4 is a plan view of the complete machine,

Fig. 5 is a vertical sectional view of one of the valves and the operating arm therefor, and

Fig. 6 is a vertical sectional view of the check valve.

The numeral 1 indicates the base upon which a cylinder 2 is formed, said cylinder having removable ends 3 and 4. The end

4 is provided with a central boss 5 forming a packing gland with suitable packing therein against the piston rod 7. The piston rod has a suitable solid piston 8 thereon which fits tightly within the cylinder 2. On the top of the cylinder there is cast a bearing for a horizontal slidable shaft 9, said shaft being held in place by means of a fixed bearing cap 10. The shaft 9 has two segment gears 11 and 12 mounted thereon at opposite ends of the bearing cap.

The segment gears are mounted to rotate with the shaft 9 as it is oscillated by means of the handle 13, said handle having bosses 14 and 15 connected therewith and rigidly connected with said shaft. The boss of the gear 11 has a notch therein with an inclined cam 16, while the gear 12 has a notch with an inclined cam 17 therein facing in the opposite direction from the cam 16. The boss 15 has a lug 18 which projects into the notch adjacent the inclined cam 16 and the boss 14 has a lug 19 which projects into the notch adjacent the inclined cam 17.

Suitably secured to the cylinder 2 adjacent the center thereof are two arms 20 and 21. The arm 20 carries a double bell crank lever 23 having two arms 24 and 25. The arms 24 and 25 are provided with set screws 26, 27 for the purpose of opening the valves controlled thereby at the proper time as will be later explained. At its upper end the double bell crank lever 23 passes into a notch 28 on one end of the shaft 9. At the other end of the shaft 9 there is a notch 29 to receive the upper end of a bell crank lever 30, which has an arm 31 projecting over a valve 32 for the operation of said valve as will be later explained. The arm 31 is provided with a set screw 33 for the purpose of opening the valve 32 at the proper time, the adjustment of said set screw providing the means for properly timing the opening of said valve.

The segment gears 11 and 12 are in mesh with two rack bars 36, 37 which are connected to a yoke 38, the latter in turn being connected to the piston rod 7.

The water supply is contained in a suitable receptacle 40 which has a pipe 41 leading therefrom to a downwardly opening check valve 42. A pipe 43 connects the check valve 42 with a T 44 from which a pipe 45 extends to the downwardly opening valve 46 the branch 44' extending into the cylinder 2. Adjacent the valve 46 is a

valve 47, and pipes 48, 49 extend from the two valves last mentioned into the carbonating receptacle 50, the pipe 49 extending nearly to the bottom of said carbonating receptacle.

The carbonating receptacle has a plurality of perforated plates 51 therein to compel the water to travel slowly through a stream of CO_2 let into the receptacle 50 from the carbon dioxide tank 52, said tank having suitable piping and a regulating valve 53 to maintain the proper pressure within the receptacle 50. From the valve 47 a pipe 54 extends around the cylinder 10 and is connected with a T 55, one branch of which 56 is connected with the cylinder head 3. From the other branch of the T 15 a pipe 57 extends to the outlet valve 32, said valve having a spout 58 thereon to allow the escape of liquid from the cylinder when a charge is to be withdrawn therefrom. The T 55 has a partition 55' to direct the incoming liquid into the cylinder instead of trapping the air and gas in the 20 pipe 57.

The operation of the carbonating machine is as follows: Assuming the tank 40 to be filled or partially filled with water the operating handle 13 is operated to draw a charge 30 of water into the cylinder 2 by moving it to the right, Figs. 3 and 4. When the handle is moved to the right, Figs. 3 and 4, the cam on the segment gear 11 will throw the handle so as to close both of the valves 46, 47 35 and at the same time the valve 32 will be opened. The movement of the handle continues until it assumes the position shown in Fig. 3, thereby moving the piston to force any water in the cylinder out through the 40 discharge pipe. As soon as the handle reaches the end of its throw it may be moved to the left (Fig. 3) whereupon the cam 17 will at once cause the handle to move laterally along its axis or down Fig. 4, the movement of the shaft 9 closing the valve 32 and 45 opening both of the valves 46 and 47 thereby equalizing the pressure at both ends of the cylinder 2. Since there is a downwardly opening check valve 42 below the tank 40 on the water supply pipe the water cannot 50 be blown out of the cylinder. When the pressure has been equalized on both ends of the cylinder 2, the dead water therein may be transferred to the charging cylinder 55 easily by moving the handle and piston to the reverse position, a supply of charged water taking its place on the opposite side of the piston. When the handle is moved to the 60 left hand position opposite to that shown in Fig. 3, the left hand end of the cylinder has received its charge as above mentioned and the handle may then be moved to the right to the position shown in Fig. 3. The first 65 result of the movement to the right will be to move the handle laterally along its axis

by the cam 16, see Fig. 4, the shaft 9 bearing on the bell crank lever 30 and lifting the lever 28 thereby closing both valves 46, 47 and opening the valve 32. As soon as the handle starts to move to the right hand 70 position Fig. 3, the valve 32 is opened, the air or gas trapped in the cylinder will be blown out and the handle may be moved to the position shown in Fig. 3 thereby delivering a charge of carbonated water. The 75 cycle of operations may be repeated as often as desired.

Having thus described my invention what I claim as new and desire to secure by Letters Patent of the United States, is as follows, express reservation being made of permissible modifications:

1. A carbonating machine comprising a pump cylinder, a liquid supply receptacle connected with the pump cylinder, a charging cylinder, connections on opposite ends of the pump cylinder extending to the charging cylinder, a check valve between the supply receptacle and pump cylinder, two valves between the charging cylinder and pump cylinder, a discharge spout having a connection extending therefrom to the top of the pump cylinder, a discharge valve with which said discharge spout is connected, a piston in the pump cylinder, a handle having means connected therewith to operate the piston, means operated by the handle to open the discharge valve when the two valves on the pipes leading from the discharge receptacle are closed, and means to open the two valves on the charging receptacle when the discharge valve is closed.

2. A carbonating machine comprising a pump cylinder, a liquid supply receptacle connected with the pump cylinder, a check valve in the connection between the supply receptacle and pump cylinder, a gas charging receptacle, connections between the gas charging receptacle and opposite ends of the pump cylinder, two valves on the connections between the charging receptacle and pump cylinder, a discharge spout having a connection with the upper portion of the pump cylinder, a valve with which said discharge spout is connected, a piston, a pivoted handle, connections between the handle and piston for operating the piston, means whereby the discharge valve is opened when the handle is moved in one direction, the valves on the pipes leading from the charging receptacles being then closed, and means to open the valves on the charging receptacle when the operating handle is moved in the opposite direction.

3. A carbonating machine comprising a pump cylinder, a liquid supply receptacle connected with the pump cylinder, a valve on the connection between the pump cylinder and supply receptacle, a charging cylinder, pipe connections from the charging 130

cylinder to opposite ends of the pump cylinder, two valves interposed between the pump cylinder and the pipes leading to the charging cylinder, a discharge pipe connected with the top of the pump cylinder at one end thereof, a valve on said discharge pipe, means for supplying CO_2 to the charging cylinder, a piston in the pump cylinder, a handle for operating said piston, 5 means whereby the discharge valve will be opened when the handle is moved in one direction, and means whereby the two valves on the pipes leading from the charging cylinder will be opened when the operating 10 handle is moved in the opposite direction.

4. A carbonating machine comprising a pump cylinder, a liquid supply receptacle connected with the pump cylinder, a check valve on the connection between the liquid 20 supply receptacle and pump cylinder opening toward the pump cylinder, a charging cylinder having pipe connections with opposite ends of the pump cylinder, a valve on each of the latter pipes, a discharge pipe connected with the top of the end of the cylinder opposite to the supply pipe, a valve on said discharge pipe, a piston in the pump cylinder, a pivoted operating handle, means whereby the discharge valve may be opened 25 by the operation of the handle, means whereby the two valves on the pipes leading from the charging cylinder may be opened when the discharge valve is closed, and means to supply the charging cylinder with 30 carbon dioxid.

5. A carbonating machine comprising a pump cylinder, a solid piston therein and an operating lever, connections between the piston and operating lever, a liquid supply 40 receptacle, a pipe connection between the liquid supply receptacle and one end of the pump cylinder, a check valve in said pipe connections opening toward the pump cylinder, a charging cylinder, pipes connecting 45 said charging cylinder with opposite ends of the pump cylinder, a valve for each of the latter pipes, a bell crank lever moved by the operating lever for opening the discharge valve, a double bell crank lever for opening 50 the two valves on the pipes leading to the charging cylinder when the discharge valve is closed, and means to supply the charging cylinder with carbon dioxid under pressure.

55. 6. In a carbonating machine, a pump cylinder, a solid piston therein and an operating lever, connections between the operating lever and piston, a liquid supply receptacle, a pipe connection between the liquid supply 60 receptacle and one end of the pump cylinder, a check valve on the pipe connection between the supply receptacle and pump cylinder and opening toward the pump cylinder, a charging receptacle, two pipes extending 65 from the charging receptacle to opposite

ends of the pump cylinder, a valve for each of said pipes, a discharge valve, a bell crank lever for operating said discharge valve, a double bell crank lever for operating the two valves on the pipes leading from the 70 charging receptacle, and means whereby the handle will be shifted laterally to open the discharge valve when moved in one direction and to open the two valves on the pipes leading from the charging receptacle when 75 moved in the opposite direction.

7. A carbonating machine comprising a pump cylinder, a solid piston therein, an operating lever pivotally connected with the pump cylinder, rack bars connected with the piston, segment gears in mesh with said rack bars, means whereby said segment gears will be operated by the handle for the operation of the piston, a liquid supply receptacle, a pipe connecting the liquid supply receptacle 80 with one end of the pump cylinder, a check valve on said pipe opening toward the pump cylinder, a charging receptacle, pipes leading from the charging receptacle to opposite 85 ends of the pump cylinder, a valve on each of said pipes, a discharge pipe leading from the upper portion of one end of the pump cylinder, a valve on said discharge pipe, means whereby the handle may be operated to open the discharge valve when 90 moved in one direction and to open the two valves on the pipes leading from the charging cylinder when moved in the opposite direction, and means to supply the charging cylinder with carbon dioxid under pressure. 100

8. In a carbonating machine, a pump cylinder, a piston therein, an operating lever pivoted on the pump cylinder, rack bars on opposite sides of the pump cylinder connected with the pump cylinder, segment 105 gears in mesh with said rack bars, means whereby the operating lever will be connected with one of said segment gears to move the piston in one direction and with the other of said segment gears to move the 110 piston in the opposite direction, a liquid supply receptacle, a pipe extending from the liquid supply receptacle to one end of the pump cylinder, a check valve on said pipe extending toward the pump cylinder, a 115 charging receptacle, means to supply said charging receptacle with CO_2 under pressure, a pipe leading from the charging receptacle to opposite ends of the pump cylinder, a valve on each of said pipes, a discharge pipe connected with the upper portion of the pump cylinder, a discharge valve with which said discharge pipe is connected, means whereby the operating lever will be moved laterally to open the discharge valve 120 when it is moved in one direction, and means whereby it will be moved laterally in the opposite direction to open the valves on the pipes leading from the charging cylinder 125 when moved in the opposite direction. 130

9. A carbonating machine comprising a pump cylinder, a solid piston therein, an operating lever pivotally supported by the pump cylinder, a pair of rack bars, connections between the rack bars and pump piston for the movement of the latter, a pair of segment gears in mesh with said rack bars, a liquid supply receptacle, a pipe extending from the liquid supply receptacle to the 10 pump cylinder, a charging cylinder, means to supply said charging cylinder with CO_2 under pressure, pipes leading from the charging cylinder to opposite ends of the pump cylinder, a valve on each of the latter

pipes, a discharge pipe, a discharge valve on 15 said discharge pipe, bell crank levers for opening the discharge valve and the valves on the pipes leading from the charging receptacle, and cams on the hubs of the segment gears for shifting the operating lever laterally to open the discharge valve or the two valves on the pipes leading from the charging cylinder and to lock said operating lever with said segment gears alternately.

In testimony whereof I have hereunto set 25 my hand this 19th day of May A. D. 1916.

THOMAS MILLWARD.

Copies of this patent may be obtained for five cents each, by addressing the "Commissioner of Patents, Washington, D. C."
